UNITED STATES PATENT OFFICE

NORMAN CLAYBAUGH DE LOSS, OF CLEVELAND HEIGHTS, OHIO

LOOSE-LEAF BINDER

Application filed November 13, 1926. Serial No. 148,163.

My invention relates to improvements in loose-leaf binders and more particularly it relates to binders of the type having provisions for automatically contracting the covers 5 thereof.

One of the objects of my invention is to provide a loose-leaf binder wherein the automatic contracting mechanism therefor is disposed mostly in one of the covers of the 10 binder.

Another object of my invention is to provide an improved automatically contractible loose-leaf binder, one of the covers of which is adapted to support a braking mechanism 15 for retarding movement of the contracting mechanism in any of its positions.

Another object of my invention is to provide an improved automatically contractible loose-leaf binder, the covers of which may be 20 retained in any of their open positions.

Another object of my invention is to provide an improved loose-leaf binder wherein the covers of the same may be prevented from closing rapidly accidentally. 25

Another object of my invention is to provide an improved attachment for expandible loose-leaf binders which will prevent the leaves from being thrown out of engagement with the binder straps when the covers are in 30 open position.

Another object of my invention is to provide an improved loose-leaf binder wherein the leaves of the same are prevented from tipping or becoming disengaged from the 35 binder straps when the covers of the binder are in open position or are being moved into any of the open or closed positions.

Another object of my invention is to provide a mechanism of the class set forth which is durable in construction, readily operable and economical to manufacture. 40

Other objects of my invention and the invention itself will become apparent from reference to the following description of an embodiment thereof and the accompanying drawings forming a part of this specification wherein:

Fig. 1 is a perspective view of the binder 50 embodying my invention;

Fig. 2 shows a side elevational view of the same;

Fig. 3 is a fragmentary transverse sectional view taken on the line 3—3 of Fig. 4;

Fig. 4 is a plan view partly broken away 55 of the binder in opened position;

Fig. 5 is a transverse sectional view taken on the line 5—5 of Fig. 4;

Fig. 6 is an enlarged sectional view of an 60 embodiment of the brake mechanism taken on line 6—6 of Fig. 4;

Fig. 7 is a vertical sectional view taken on line 7—7 of Fig. 4;

Fig. 8 is an elevational view of a fragment 65 of the binder, illustrating an expanded position of the same;

Fig. 9 is a side elevational view of a fragment of the clincher bar.

Referring to all the figures of the drawings in all of which like parts are designated by like reference characters. At 1 I show in general a loose-leaf binder having at 2 and 3 top and bottom covers respectively, and at 4 a plurality of leaves disposed between the covers and retained therebetween by a pair of binder straps 22 and 23. Clincher bars 6 and 7 are hingedly connected to inner ends of the covers by virtue of pairs of hinges 8—8 and 9—9 oppositely disposed in recesses 10, 11, 12 and 13 provided in the clincher bars and 70 cover ends respectively. Preferably the inner ends of the covers and the adjacent sides of the clincher bars are formed into complementary angle formation as at 14 and 15 on a diagonal plane, the hinges being secured preferably at the outer edges of the diagonal faces of the clincher bars and covers. Preferably 75 the inner ends of the covers are provided with pairs of equally spaced apertures 60 and 61, and pairs of apertures 62 and 63 are also provided in the clincher bars normally at right angles to the openings 60 and 61, and so disposed that they will register with each other when the binder covers are in closed position, for a purpose which will hereinafter 80 be described.

Each of the covers of my improved binder is preferably constructed of a skeleton frame of light metal such as aluminum comprising top and bottom spaced frame sec- 85

100

tions 16 and 17 having transverse cross-pieces 18, 19, and 20. However, it is to be understood that I may employ a rigid material other than a metallic material to construct the sections of the skeleton frame. Spacer bars 21 of a suitable binder material, (or sometimes I may employ a light angle-formed metallic bar), are interposed between the frame sections of each cover, and secured between the same by bolts, rivets or the like, to provide a unitary structure. I sometimes contemplate employing wooden strips as spacer bars and in such cases I may employ a suitable glue for the purpose of securing the sections of the frame and the spacer bars together. A binder-covering material such as leather or buckram encloses the skeleton frame and gives the same the appearance of a book cover.

Preferably the contracting mechanism is mounted in the chamber 25 of the cover 2 and comprises a pair of spring-rotated drums preferably somewhat similar in construction to the carriage-return spring drums commonly employed on standard typewriters, comprising a casing portion 26, peripheral flanges 28 and 29 defining a channel portion 27 and a convolute spring 30, one end of which is secured to the casing 26 and the other end thereof is secured in a slot 150 in a shaft 31 about which the casing may rotate against the tension of the spring 30. The shaft 31 has projecting bearing portions 32 and 33 which are adapted to be inserted into apertures 34 provided in the intermediate cross bar 18 to form bearings for the drums. One of the spring drums is adapted for rotation clockwise while, the other is adapted for rotation counter-clockwise. Inasmuch as the spring drums are similar in construction to each other, only one of them has been described in detail.

Secured to the casing portion of the spring drums are the pair of flexible binder straps 23 and 22 formed of metallic cable or the like. These straps partially surround the drums and are disposed in the channels formed in the drums by the peripheral flanges 28 and 29 thereof. These straps leave the drums tangentially at sides of the drums opposite each other and disposed in parallel relation with each other and are adapted to pass through the opening in the end wall of the cover and through openings in the clincher bars and through openings in the end wall of the other cover of the binder wherein they are anchored at 70 to a spacer bar 21 in any suitable manner such, for example, as by a wrapping of wire about the end of the strap.

Each of the leaves 4 of the binder is provided preferably with a pair of aligned holes 50 at its inner end for the reception of the straps having slots 51 cut in the same from the hole to the edge of the sheet to permit the leaves to be placed on to the binder straps.

The slots 51 are slightly less in width than the diameter of the binder straps and the holes 50, so that when the leaves have been placed on the binder straps they will not permit the leaves to slide off the same.

The brake mechanism heretofore referred to comprises preferably a wedge-shaped brake shoe 37 disposed in close proximity to the peripheral flanges 28 of the two spring drum casings between the same and is provided with a rearwardly extending stem 40. The shoe is of such a size that it will engage but one of the peripheral flanges on the drums without engaging the binder straps. However, if desired, the shoe may be made larger in size so that it may engage both peripheral flanges of each of the spring drums without contacting with the straps which are disposed in the channels of the spring drums out of possible contact with the brake shoe so that the wear on the strap by the brake shoe is completely avoided. The cross bar 20 of the cover frame is provided on its inner surface with a collet 41, secured thereto preferably by screws and provided with a central bore 42 into which the end of the stem 40 is adapted to project, the bore permitting reciprocation of the stem therein. A compression spring 43 is interposed between the brake shoe and the collet 41 and is coiled about the stem and adapted to normally exert a pressure upon the shoe to force it into braking engagement with the peripheral flanges of the drums. A collet 46 is carried on the inner side of the cross-frame member 20 having an aperture therethrough in alignment with the aperture in the collet 41 for the reception of the stem portion 47 of the brake. The inner wall portion of the binder adjoining the leaves is pierced to form a slot 44 adjacent the edge of the cover through which a lug 45 projects, preferably formed integral with the brake shoe and being of an arcuate configuration to conform generally to the shape of a human thumb. Preferably the lug is so positioned relative to the edge of the binder that it may be conveniently engaged by the thumb of an operator when the cover has been gripped to open or close the loose leaf binder.

The brake shoe may be so positioned relative to the pair of spring drums that the brake effect exerted by the brake shoe by virtue of the tension of the compression spring will be such that the spring drums will not be prevented from operating to permit the binder to be pulled open, in which action the spring drums will be rotated in the direction of the arrows 86 and 87 as shown in Fig. 4 of the drawings. However, when the binder covers are expanded the brake shoe will prevent their returning to closed position by virtue of the fact that the spring drums, each rotated in the opposite direction of the arrows 86 and 87 will cause the brake shoe to be wedged between the flanges of the spring

drums and prevent relative movement of the same.

I contemplate sometimes forming the 5 brake shoe and peripheral edges of the flanges of the drums with teeth to effect a more positive gripping action between the brake shoe and the drums.

Assuming the binder to be in the position illustrated in Fig. 2 of the drawings and it is desired to place additional leaves in the 10 binder or to remove leaves therefrom, the cover carrying the contracting binder mechanism is swung open and pulled away from the other cover to an expanded position 15 shown in Fig. 8 of the drawings. In this position leaves may be inserted or removed from the binder as desired, the binder being retained in its expanded position by virtue of the 20 brake shoe 39. When it is desired to permit the binder to contract, the operator 25 grips the top cover in his hand adjacent the projecting lug 45 and reciprocates the latter towards the edge of the cover and thereby reciprocates the brake shoe away from the peripheral flanges of the drums against the 30 tension of the spring 43, accordingly the brake on the automatic contracting mechanism is released and the spring drums will then exert a pull upon the binder straps and thereby cause the other cover to be pulled 35 toward the first cover carrying the automatic contracting mechanism and the brake. The binder has now been contracted and the leaves 40 are properly gripped between the clincher bars 6 and 7.

When it is merely desired to employ the binder without removing or replenishing the supply the leaves thereof the binder may be 45 swung into the position shown in Fig. 5 of the drawings, the leaves 4 thereof being retained generally in the position shown by virtue of the clamping action of the clincher bars 6 and 7 so that there is no possibility of the leaves accidentally jumping off of the 50 binder straps clear of the binder.

It will be readily understood from the foregoing that my improved binder may be expanded to any thickness by varying the length of the binder straps or by varying the 55 point at which the binder strap is secured to the spring drum. Preferably, I employ binder straps and so position them on the spring drums that the binder may be expanded to a thickness of approximately six inches. It will be apparent also that the 60 binder will not close rapidly when in open position nor will it accidentally close when in open position due to the effect of the brake on the spring drums which retain the same locked in position when the binder has been 65 opened or expanded.

The binder covers and expansible mechanism and brake are formed of materials which are durable in construction and which 70 will not readily become broken or out of order. The only parts employed in my improved binder which may become worn are the straps which are preferably formed of a flexible material. However, these straps may be replaced at a relatively slight cost. 75

Having thus described my invention in a specific embodiment, I am aware that numerous and extensive departures may be made from the embodiment herein illustrated and described but without departing from the 80 spirit of my invention,

I claim:

1. In a loose leaf binder, the combination of a top cover and a bottom cover, a retracting mechanism for connecting the covers to each other, said mechanism comprising a pair of drums journaled in one of the covers, retractile springs secured in said drums adapted to constantly exert a pressure tending to rotate the drums by virtue of their effort to 85 retract, and a pair of binder straps, one end of each of the binder straps being secured to the drums, the opposite end thereof being anchored to the opposed cover, said spring-actuated drums constantly exerting a pull 90 upon the binder straps to normally draw the covers towards each other, and a brake carried adjacent the drums and adapted to frictionally engage the same for restraining rotation of the drums. 95

2. In a loose leaf binder, the combination of a top cover and a bottom cover, a retracting mechanism for connecting the covers to each other, said mechanism comprising a pair of drums, said covers each comprising a pair of spaced skeleton frame members, said drums journaled in said skeleton frames, springs secured in said drums adapted to constantly exert a pressure tending to rotate the drums by virtue of their effort to retract 100 and a pair of binder straps, one end of each of the binder straps being secured to the drums, the opposite end thereof being anchored to the opposed cover, said spring-actuated drums constantly exerting a pull upon 105 the binder straps to normally draw the covers towards each other, and a brake carried adjacent the drums and adapted to frictionally engage the same for restraining rotation of the drums. 110

3. In a loose leaf binder, the combination of a top cover and a bottom cover, a retracting mechanism for connecting the covers to each other, said covers each comprising a pair of spaced skeleton frame members, and providing a space in which a pair of drums are journaled for rotation, said mechanism comprising said drums, retractile springs secured in said drums adapted to constantly exert a pressure tending to rotate the drums 115 by virtue of their effort to retract, and a pair of binder straps, one end of each of the binder straps being secured to the drums, the opposite end thereof being anchored to the opposed cover, said spring-actuated drums 120 125 130

constantly exerting a pull upon the binder straps to normally draw the covers towards each other, and a brake carried adjacent the drums and adapted to frictionally engage the same for restraining rotation of said drums.

4. In a loose leaf binder, the combination of a top cover and a bottom cover, a retractile mechanism for connecting the covers to each other, said covers each comprising a pair of spaced skeleton frame members, and providing a space in which a pair of drums are journaled for rotation, said mechanism comprising said drums, retractile convolute

10 springs having their ends secured within said drums adapted to constantly exert a pressure tending to rotate the drums by virtue of their effort to retract, and a pair of binder straps, one end of each of the binder straps being secured to the drums, the opposite end thereof being anchored to the opposed cover, said spring-actuated drums constantly exerting a pull upon the binder straps to normally draw the covers towards each other, said drums

15 comprising spaced skeleton disk members having a channel portion therebetween for the binder straps.

5. In a loose leaf binder, the combination of a top cover and a bottom cover, a retracting mechanism for connecting the covers to each other, said mechanism comprising a pair of drums carried by one of the covers, retractile convolute springs secured to said drums adapted to constantly exert a pressure tending to rotate the drums by virtue of their effort to retract, and a pair of binder straps connected to the drums at one end and being anchored at their opposite ends to the other cover, and a clincher bar hingedly carried by each of the covers, said spring-actuated drums constantly exerting a pull upon the binder straps to normally draw the covers and the clincher bars towards each other, said clincher bars adaptable to engage a plurality of leaves therebetween to bind the same together by virtue of the pull imparted to it by the binder straps.

6. In a loose leaf binder, the combination of a top cover and a bottom cover, a retracting mechanism for connecting the covers to each other, said mechanism comprising a pair of drums carried by one of the covers, retractile convolute springs secured to said drums adapted to constantly exert a pressure tending to rotate the drums by virtue of their effort to retract, and a pair of binder straps connected to the drums at one end and being anchored at their opposite ends to the other cover, and a clinched bar hingedly carried by each of the covers, said spring-actuated drums constantly exerting a pull upon the binder straps to normally draw the covers and the clincher bars towards each other, said clincher bars adaptable to engage a plurality of leaves therebetween to bind the same

70 together by virtue of the pull imparted to it by the binder straps, and braking means carried adjacent the drums and adapted to frictionally engage the same for restraining relative movement of the covers.

7. In a loose leaf binder, the combination of a top cover and a bottom cover, a retracting mechanism for connecting the covers to each other, said mechanism comprising a pair of drums journaled in one of the covers, retractile springs secured in said drums adapted to constantly exert a pressure tending to rotate the drums by virtue of their effort to retract, a pair of binder straps, one end of each of the binder straps being secured to the drums, the opposite end thereof being anchored to the opposed cover, said spring-actuated drums constantly exerting a pull upon the binder straps to normally draw the covers towards each other, and a brake member carried by one of the covers and having a shoe portion disposed between the drums and adapted to frictionally engage the same for locking the same against rotation.

8. In a loose leaf binder, the combination of a top cover and a bottom cover, a retracting mechanism for connecting the covers to each other, said mechanism comprising a pair of drums carried by one of the covers, retractile springs secured in said drums adapted to constantly exert a pressure tending to rotate the drums by virtue of their effort to retract, a pair of binder straps, one end of each of the binder straps being secured to the drums, the opposite end thereof being anchored to the opposed cover, said spring-actuated drums constantly exerting a pull upon the binder straps to normally draw the covers towards each other, and a brake member carried by one of the covers, said brake member comprising a reciprocable brake shoe, a coiled spring compressed to the rear of the shoe for normally pressing the shoe into engagement with the brake drums for restraining relative movements of the covers by virtue of the retractility of the coiled spring.

9. In a loose leaf binder, the combination of a top cover and a bottom cover, a retracting mechanism for connecting the covers to each other, said mechanism comprising a pair of drums carried by one of the covers, retractile springs secured in said drums adapted to constantly exert a pressure tending to rotate the drums by virtue of their effort to retract, a pair of binder straps, one end of each of the binder straps being secured to the drums, the opposite end thereof being anchored to the opposed cover, said spring-actuated drums constantly exerting a pull upon the binder straps to normally draw the covers towards each other, and a brake member carried by one of the covers, said brake member comprising a brake shoe, a spring compressed to the rear of the brake shoe and

adapted to normally press the brake shoe between the brake drums to simultaneously engage each of the drums for restraining relative movement thereof.

5 10. In a loose leaf binder, the combination with a pair of relatively movable covers, of a binder contracting mechanism in one of said covers, comprising rotatable drums journaled in one of the movable covers, retracting 10 cords extending between the covers windable on the drums, a brake in frictional engagement with the drums to normally restrain relative movement of the covers, and manually operative means to release the brake.

15 11. In a loose leaf binder a pair of relatively movable covers, a pair of rotatable drums and spring rotating means for the drums in one of the covers, cords secured to the other cover windable on said drums, a 20 brake in frictional engagement with portions of both drums adapted to restrain the drums from pulling the cords to cause relative movement of the covers.

25 12. In a loose leaf binder, a pair of relatively movable covers, one of said covers comprising a skeleton frame, a rotatable drum journaled in the frame, a brake for the drum, said brake comprising a brake shoe, a spring normally pressing the shoe into engagement 30 with the drum, a cord windable on the drum and secured thereto and secured at the other end to the other cover and a manually engageable trigger to release the brake.

35 13. In a loose leaf binder, the combination of a pair of covers, ends for the covers, each end and its cover being hingedly secured together, drums journaled in one of said covers, springs in said drums connected thereto, a plurality of flexible straps each having an 40 end thereof connected to the other of the covers and the opposite end thereof secured to a drum, said springs normally adapted to exert a torque on the drums, which torque is imparted to the straps to draw the cover ends 45 towards each other to adapt them to clamp a plurality of leaves inserted therebetween.

50 14. In a loose leaf binder, the combination with a pair of covers, means for connecting the covers in spaced relation to each other, drums journaled in one of said covers, springs in said drums connected thereto, and a plurality of flexible straps, having an end thereof secured to the other of said covers and the opposite end thereof secured to the drums, 55 said springs normally operating said drums to cause a tension upon the straps to draw the covers towards each other.

50 15. In a loose leaf binder, the combination of a pair of relatively movable hinged covers, ends for the covers, each end and its cover being hingedly secured together, a retracting mechanism mounted in one of said covers, a 60 plurality of flexible straps, each having an end thereof connected to the other of the covers and the opposite end thereof secured

to the retracting mechanism, said retracting mechanism normally exerting a tension upon the straps to draw the cover ends towards each other to adapt them to clamp a plurality of leaves inserted therebetween, and a 70 brake carried by a cover adjacent the retracting mechanism adapted to normally restrain movement thereof.

16. In a loose leaf binder, the combination with a pair of relatively movable covers, means for connecting the covers in spaced relation to each other comprising a retracting mechanism mounted in one of the covers and a plurality of flexible straps, each strap having an end thereof secured to one of said 75 covers and the opposite end thereof secured to the retracting mechanism, said mechanism normally exerting a tension upon the straps to draw the covers towards each other, and a 80 brake carried by a cover adjacent the retracting mechanism adapted to normally restrain movement thereof.

17. In a loose leaf binder, the combination of a pair of relatively movable covers, a pair of clincher bars, each hinged to a different 90 one of the covers, a retracting mechanism, and a plurality of flexible straps having one end thereof anchored to one of the covers and the opposite end thereof secured to the 95 retracting mechanism within the other cover, said mechanism normally exerting a tension upon the binder straps to draw the clincher bars towards each other to clamp a plurality of loose leaves when interposed therebetween.

18. In a loose leaf binder, the combination 100 with a pair of relatively movable covers, a retracting mechanism carried by one of said covers and securing the covers to each other, comprising a plurality of drums, retractile 105 springs in said drums, a pair of flexible binder straps having one end connected to said drums, and the other end to the other cover, said drums adapted to exert a tension on the binder straps by virtue of the retractability of the springs contained therein to 110 draw the covers towards each other.

19. In a loose leaf binder, the combination 115 with a pair of relatively movable covers, a retracting mechanism carried by one of said covers and securing the covers to each other, comprising a plurality of drums, retractile springs in said drums, a pair of flexible binder straps having one end connected to said drums, and the other end to the other cover, 120 said drums adapted to exert a tension on the binder straps by virtue of the retractability of the springs contained therein to draw the covers towards each other, and a brake mounted in one of the covers adjacent the retracting mechanism and adapted to engage therewith to normally restrain movement thereof.

20. In a loose leaf binder, the combination 125 with a pair of relatively movable covers, a retracting mechanism carried by one of 130

said covers and securing the covers to each other, comprising a plurality of drums, retractile springs in said drums, a pair of flexible binder straps having one end connected to said drums, and the other end to the other cover, said drums adapted to exert a tension on the binder straps by virtue of the retractility of the springs contained therein to draw the covers towards each other, a spring 10 pressed brake member carried by one of the covers adjacent the retracting mechanism, said brake having a shoe portion normally engageable with the said retractile mechanism.

21. In a loose leaf binder, the combination with a pair of relatively movable covers, a retracting mechanism carried by one of said covers and securing the covers to each other, comprising a plurality of drums, retractile 20 springs in said drums, a pair of flexible binder straps having one end connected to said drums, and the other end to the other cover, said drums adapted to exert a tension on the binder straps by virtue of the retractility of the springs contained therein to draw the covers towards each other, a spring-pressed brake member carried by one of the covers adjacent the retracting mechanism, said brake having a shoe portion normally engageable with the said retractile mechanism, said brake having a laterally projecting portion engageable by the finger of an operator for reciprocating the brake shoe out of contact with the binder mechanism against the tension of said spring.

22. In a loose leaf binder, the combination of a pair of covers, ends for the covers, each end and its cover being hingedly secured together, a retracting mechanism mounted in one of said covers, a plurality of flexible straps, each having an end thereof connected to the other of the covers and the opposite end thereof being secured to the retracting mechanism, said retracting mechanism comprising spring-operated winding devices for the straps adapted normally to exert tension on the straps to draw the cover ends toward each other to adapt them to clamp a plurality of leaves inserted therebetween and a brake carried by said first cover adjacent the drum devices adapted to normally restrain movement thereof.

23. In a loose leaf binder, the combination of a pair of relatively hinging covers, a retracting mechanism mounted in one of said covers, a plurality of flexible straps, each having an end thereof connected to the other of the covers and the opposite end thereof secured to the retracting mechanism, said retracting mechanism comprising a pair of spring-operated winding drum devices, normally exerting tension upon the straps to draw the covers toward each other, the drum devices being provided with annular braking surfaces and a brake carried by said first

cover adjacent the winding devices adapted normally to engage the braking surfaces thereof and thereby restraining winding movement thereof.

24. In a loose leaf binder, the combination of a pair of relatively hinging covers, a retracting mechanism mounted in one of said covers, a flexible strap having an end thereof connected to the other of the covers and the opposite end thereof being secured to the retracting mechanism, said retracting mechanism comprising a spring-operated winding device for the strap normally exerting a tension on the strap to draw the covers toward each other, the winding device being provided with an annular braking surface, and a brake carried by said first cover adjacent to the retracting mechanism adapted normally to engage the braking surface and restrain winding movement of the drum device.

In testimony whereof I hereunto affix my signature this 27th day of September, 1926.
